(57) **CLAIM**

I claim the ornamental design for the double barb arrow for use with a sterilization container latch, as shown and described.

DESCRIPTION

FIG. 1 is a top perspective view of a double barb arrow for use with a sterilization container latch showing my new design;

FIG. 2 is a top view thereof;

FIG. 3 is a bottom view thereof;

FIG. 4 is a right side view thereof;

FIG. 5 is a left side view thereof;

FIG. 6 is a front end view thereof; and,

FIG. 7 is a back end view thereof.
